UNITED STATES PATENT OFFICE.

WILLIAM NEUSWANGER, OF GLENWOOD SPRINGS, COLORADO.

DESIGN FOR A PEN AND PENCIL CLIP BLANK.

58,618.

Specification for Design.

Patented Aug. 2, 1921.

Application filed January 28, 1919. Serial No. 273,657. Term of patent 14 years.

To all whom it may concern:

Be it known that I, WILLIAM NEUSWANGER, a citizen of the United States, and a resident of Glenwood Springs, in the county of Garfield and State of Colorado, have invented a new, original, and ornamental Design for a Pen and Pencil Clip Blank, of which the following is a specification, reference being had to the accompanying drawings, forming part thereof.

Figure 1 shows a plan view of the blank.
Fig. 2 shows a side elevation of the blank.
Fig. 3 shows a cross-sectional view, taken on the line 3—3 of Fig. 1.

I claim:

The ornamental design for a pen and pencil clip blank, as shown.

Des Moines, Iowa, December 10, 1918.

WILLIAM NEUSWANGER.
